Filed Apr. 5, 1962, Ser. No. 69,601

Term of patent 14 years

(Cl. D29—17)

The FIGURE is a plan view of a military campaign pennant or other similar article showing my new design.

The back of the pennant is conventional, and portions are lined to indicate color contrast rather than any specific color. The essential features of the design reside in the portions shown in full lines and consist primarily in the representation of the rifle at the top together with the intertwined barbed wire and the exploding grenade and landing craft scene on the field substantially as shown.

I claim:

The ornamental design for a military campaign pennant or other similar article as shown and described.
